UNITED STATES PATENT OFFICE.

SAMUEL M. WINKLER, OF NEW YORK, N. Y.

DESIGN FOR A SHOE HEEL.

Application filed May 13, 1926. Serial No. 17,690. Term of patent 3½ years.

To all whom it may concern:

Be it known that I, SAMUEL M. WINKLER, a citizen of the United States of America, residing at New York city, New York County, State of New York, have invented a new, original, and ornamental Design for a Shoe Heel, of which the following is a specification, reference being had to the accompanying drawing, forming part hereof, in which—

Fig. 1 is a side elevation of a shoe heel showing my new design, Fig. 2 is a similar view of the opposite side of the shoe heel and Fig. 3 is a rear view thereof.

I claim:

The ornamental design for a shoe heel as shown.

Signed at New York city, this 11 day of May, 1926.

SAMUEL M. WINKLER.
